UNITED STATES PATENT OFFICE.

DAVID KIEL TULLIS, OF GLASGOW, SCOTLAND.

LEATHER LINK AND LEATHER LAMINATED BELTING.

1,250,247.

Specification of Letters Patent. Patented Dec. 18, 1917.

Application filed March 1, 1917. Serial No. 151,864.

To all whom it may concern:

Be it known that I, DAVID KIEL TULLIS, of 10 Eglinton Drive, Kelvinside, Glasgow, Scotland, have invented certain new and useful Improvements in and Connected with Leather Link and Leather Laminated Belting, of which the following is a specification.

My invention relates to improvements in and connected with leather link and leather laminated belting, and has for its object to construct such belting as to obviate the heads of the rivets in the link belting and the sewing in the laminated belting from being destroyed, thereby increasing the life of the belting.

In carrying out my invention, I form the outer strands of the belt of U-shape, *i. e.*, broader or deeper than the other strands, or other such suitable shape, as will, when the belting is built up, have the sewing or rivet heads completely covered or protected. These outer strands of the belting are composed of leather of rather a softer nature than that of the strands forming the belting, so as to accommodate themselves to the stretching of the belting, and also allow great strain to be taken off the rivets on the link belting, and the main sewing of the laminated belting. The edges of outer strands may be blocked, or folded or pressed to the shape required or they may be sewn, or riveted or the like, to form the necessary shape, and they may have a tongue or fillet interposed so as to fill in any hollow which may be formed by the shape of the outer strands.

In order that my invention may be properly understood and readily carried into effect, I have hereunto appended one sheet of drawings, of which

Figure 1 is a transverse section of a laminated leather belting for transmitting power made in accordance with and embodying my invention.

Fig. 2 is a horizontal section of the same taken on the line *a, b*, Fig. 1.

Fig. 3 is an elevational edge view also of the same.

Fig. 4 is an elevation of the belting without any tongue or fillet.

Fig. 5 is a transverse section of a leather link belting also embodying my invention.

Fig. 6 is an elevational edge view of the

same and corresponding to Fig. 3, as hereinafter more fully referred to and described. 55

Referring to Figs. 1, 2, 3, and 4 of the drawings, the belt is built up of laminated strands *B* which terminate on both sides with strands *C* of U-formation, *i. e.*, broader or deeper than the other strands, the strands *B* and the strands *C* being held in position by the transverse wire or cord stitching *D*, Figs. 1, 2 and 4. The loops of the stitches *D* lie snugly protected within the hollow of the outer strands *C*. When the belt is made up, the outer strands are folded or pressed into such a shape as to form a protected edge to the belt, and stitched, thereby preventing injury to the otherwise exposed stitching or like attachments. 60 65 70

Tongues or fillets *E* may be inserted within the hollow or grooves of the outer strands *C*, which are held in position by the longitudinal stitching *F*, see Figs. 1 and 2, or as 75 in Fig. 4 no fillet is necessary.

Referring to Figs. 5 and 6 which illustrate a link belting, the link sections *B* after the manner of the ordinary link belting are held in position by transverse bolts or pins 80 *G*. These bolts or pins *G* also connect together the outer strands *C* of similar formation to that described. The longitudinal size and length of the strands *C* correspond to the link sections *B* as opposed to their 85 being of one continuous length as shown in the laminated belt aforementioned. The heads and ends *G* of the bolts or pins *G* and washers *H* lie snugly protected in the hollow of these outer strands *C* as seen in 90 Fig. 5, and the ends of the outer strands are folded over and pressed into such a shape as to form a protected edge to the belt and stitched, as already described.

Tongues or fillets *E* may be employed to 95 full up any grooves and hollows of the outer strands, and these are held in position by the stitching *F*, said tongues or fillets preventing injury to the otherwise exposed heads of the bolts or pins or analogous sectional attachments. 100

Claims.

1. A belt comprising in combination a plurality of longitudinally extending laminations, edge members, one on each side of said belt, and transversely extending members securing said laminations and said edge members and extending from side to side of

the belt, said edge members having outwardly extending portions forming recesses in which the ends of said transversely extending members lie, said outwardly extending portions being secured together.

2. A belt comprising in combination a plurality of longitudinally extending laminations, edge members, one on each side of said belt, and transversely extending members securing said laminations and said edge members and extending from side to side of the belt, said edge members having outwardly extending portions forming recesses in which the ends of said transversely extending members lie, said outwardly extending portions being secured together by stitching.

3. A belt comprising in combination a plurality of longitudinally extending lami-

nations, edge members, one on each side of 20 said belt, transversely extending members securing said laminations and said edge members and extending from side to side of the belt, said edge members having outwardly extending portions forming recesses 25 in which the ends of said transversely extending members lie, fillets within said recesses covering the ends of said transversely extending members, and means securing together said outwardly extending portions 30 of said edge members.

In witness whereof I affix my signature in presence of two witnesses.

DAVID KIEL TULLIS.

Witnesses:

J. MIDDLETON,
T. HAY.
